UNITED STATES PATENT OFFICE.

WILLIAM J. DROPPLEMAN, OF McWHORTER, WEST VIRGINIA.

GAS CASING HEAD.

1,398,093.

Specification of Letters Patent.

Patented Nov. 22, 1921.

Application filed March 11, 1921. Serial No. 451,457.

To all whom it may concern:

Be it known that I, WILLIAM J. DROPPLEMAN, a citizen of the United States, and resident of McWhorter, in the county of Lewis, 5 State of West Virginia, have invented certain new and useful Improvements in Gas Casing Heads, of which the following is a description, reference being had to the accompanying drawings, forming a part 10 hereof.

My invention relates to casing heads for gas and oil wells and has for its object to provide a casing head for such wells which will be simple and inexpensive in construction, comparatively light in weight, readily applied to and removed and which will be adapted to fit the collar or coupling on the upper end of the top section of the well casing so as to make a tight joint with it.

20 With these and other objects hereinafter explained in view, my invention consists in the construction and combination of elements hereinafter described and claimed.

Referring to the drawings; 25 Figure 1 is a perspective view of a casing head embodying my invention complete and ready for use.

Fig. 2 is a vertical central sectional view of the casing head shown in Fig. 1, with a 30 portion of the well casing and the coupling carried by it.

Fig. 3 is a side elevation of the section of tubing from which the body of the casing head is formed.

35 Fig. 4 is a perspective view of the top clamp, and

Fig. 5 is a perspective view of the packing ring.

In the drawings 1 indicates a section of 40 well casing, or other tubing, exteriorly screwthreaded at its lower end at 2, to fit the coupling 3 on the upper end of the top section 4 of a well casing. In forming the casing head this section of tubing is provided at its upper end with longitudinal V shaped incisions to leave between them tongues 5. These tongues are bent inward from their bases and then bent upward to inclose between them a section of smaller tubing 7, the upper ends of the tongues being bent outward to form ears 8. The tongues 5 are welded together at their edges and are welded to the section of smaller tubing 7.

The base portions of the tongues when 55 thus welded together form a somewhat dome

shaped top 6. The section of smaller tubing 7 is outwardly flared at its upper end as shown at 9, to receive a packing ring 10 which is exteriorly tapered as shown. A top clamp 11 having an opening 12 through it 60 and a depending flange 13 surrounding the opening and adapted to enter the flared upper end 9 of the smaller tubing 7 serves, when forced downward, to compress the packing ring 10 against the leading off pipe 65 14 thus insuring a tight joint. In order to force this top clamp downward it is provided with openings in line with similar openings in the ears 8 to receive bolts 15.

The body of the casing head is preferably 70 provided with laterally extending tubes 16 and 17, preferably interiorly screwthreaded, to receive lateral leading off pipes if desired. These laterally extending tubes also serve as convenient handles for carrying the casing 75 head and for rotating it to screw it into place in the coupling 3. The casing being exteriorly screwthreaded to fit within the coupling 3, if there should be any leakage, a packing ring may readily be inserted within 80 the coupling to rest on the upper end of the top section of pipe 4 and be compressed by screwing the casing head down onto it.

While I prefer to make the body of the casing head of a section of ordinary well 85 casing having the usual screwthread cut on it. It may, of course be made of special tubing. The section of tubing, whether cut from a length of casing or special tubing, from which the body of the casing head is 90 made may be of any diameter desired. Being relatively thin material, particularly if ordinary well casing is used, the casing head will be of comparatively light weight making it convenient for transportation and easily 95 handled in placing it in position.

Having thus described my invention what I claim is;

1. A casing head comprising a body formed of tubing exteriorly threaded at its 100 lower end and having its upper portion cut to form longitudinal tongues, the base portions of said tongues being bent inward and united to form a top and the outer portions bent upward and united to form a restricted 105 passage adapted to receive a leading off pipe.

2. A casing head comprising a body formed of tubing exteriorly threaded at its lower end and having its upper portion cut to form longitudinal tongues, the base por- 110

tions of said tongues being bent inward and united to form a top and the outer portions bent upward about a section of tubing of relatively small diameter and united to each other and to said section of smaller tubing.

3. A casing head comprising a body formed of tubing exteriorly threaded at its lower end and having its upper portion cut to form longitudinal tongues, the base portions of said tongues being bent inward and

united to form a top and the outer portions bent upward about a section of tubing of relatively small diameter and united to each other and to the said section of smaller tubing, the ends of the tongues being bent outward to form ears, and a top clamp secured to said ears by bolts. 15

In testimony whereof I affix my signature this 10 day of March, 1921.

WILLIAM J. DROPPLEMAN.
